UNITED STATES PATENT OFFICE

2,645,333

HAT HOLDER FOR HAT BOXES

Paul E. Nelson, Geneva, Ill.

Application March 2, 1949, Serial No. 79,157

11 Claims. (Cl. 206—8)

1

This invention is directed to a hat holder for a hat box, the holder being of such design as to lend itself to independent fabrication as a complete attachable unit, or to an identical unit that can be made out of a selected box surface as an integral part of the box without using additional box board for the formation of the holder per se.

The holder comprises a simple compact and inexpensive unit of efficient operable qualities to practically and securely support or hold a hat within a hat box and centrally thereof. Preferably this unit is adapted for attachment to the inside of the cover for the purpose of suspending a hat from the cover of the hat box with only the base portion of the hat brim disposed adjacent to the under surface of the cover. Thus the peripheral edge of the brim, the top side thereof, and the crown are positioned centrally of the box interior and away from the side walls and bottom of the box since the holder is positively located by the cover when in position upon the box bottom.

The packaging of hats has always presented an age old problem to the manufacturer that concerns supplying a customer with a hat that will reach him in the same fine finished condition that the hat is in at the time it is ready for shipment from the factory. The importance of the step of providing a hat box that will live up to the manufacturer's expectations of delivering a hat to its sale source may be well emphasized by the fact that hat factories go through a great deal of time and expense to produce hats that have properly shaped brims and crowns to conform to selected styles. In the final analysis it is self-evident that these manufacturers want their hats to reach the public in their fine ultimate condition to satisfy the customers and produce future sales.

Hat factories do go through a great deal of trouble and expense to ship hats, but invariably the methods and means used do not protect the hats properly. With all the numerous precautions used and the material resorted to the hats are received at the retail stores or other sales sources with blemishes and marks upon the brims and crowns. It has been the practice to ship several hats in a single box, but this likewise increases the markings since the hats are nested when so shipped.

In shipping one or more hats in a box it has been the practice to use packing elements such as rings, stays, discs, fillers, tissues, etc., or various combinations of these groups. However, after a great deal of care in packing hats with

these packing aids, the hats are still received in marked or scuffed condition which will be inevitable so long as methods are used wherein the hat brims or crowns are in contact with the packing materials. This unfavorable situation is multiplied where several hats are nested for shipment in one box and this method creates another problem at the store of having only one box available for several hats. One customer will then receive a box, but several others must be satisfied with soft paper bags which can be the ruin of a hat before it reaches the closet hook.

10 The hat holder of this invention has been created for the purpose of eliminating the difficulties noted and to provide a means by which a single hat to a box is to be shipped to the store in factory finished condition for transmittal directly to the customer who selects the hat. The customer buying the hat receives the box, and the holder has the further advantage of being collapsible so that future use thereof is optional but not necessary by the customer after the hat is purchased.

15 The holder reduces soiling of hats by less handling since the hat may be shown by merely taking the cover off the box with the hat attached to the underside of the cover. If the color or style is not wanted, the cover is replaced to put the hat into its protected and dust proof position within the box. Obviously, transparent box bottoms or covers may be used, or windows can be resorted to in the box bottoms if desired. And the box surface may also be used for printed matter as an advertising medium.

20 25 30 35 With a hat box of this type no packaging materials are needed which normally clutter up store space and require handling while also adding to the fire hazards of retail stores.

Another object of the holder is to provide a means to allow the choice of shipping precreased or open crown hats, although the latter may be hand creased at the factory since shipping by the present proposed method prevents the crown or crease from becoming damaged in transit. The hat shape is retained.

40 45 50 The holder is made for the accommodation of all hat sizes and needs no adjusting or individual attention since its action is entirely automatic, and it only requires placing the hat in position for reception by the holder or manual removal of the hat therefrom to remove the hat from the box.

Another advantage of the hat holder of the new design is its versatility of use with respect to the type of box used. The holder can be used in set up boxes, in folding boxes, or in any com-

bination of the two since the holder is flat until placed in operative use to hold a hat. In each of these types of boxes the holder may be made die cut out of the body of the box material all depending upon conditions of use and upon which form is most desirable to the hat maker.

Other objects and advantages relating to the hat holder of the present construction shall hereinafter appear in the following detailed description having reference to the accompanying drawings forming a part of this specification.

In the drawings:

Fig. 1 is a side elevational view of a conventional hat box embodying a hat holder of the present invention and illustrating the holder as supporting a hat for shipment, a part of the box and holder structure being broken away and indicated in section to show certain details of the hat package;

Fig. 2 is a horizontal cross sectional view through the crown of the hat looking into the cover of the box with the cover removed from the box bottom and substantially as seen along the line 2—2 in Fig. 1;

Fig. 3 is a plan view of the die cut holder blank as the same appears in its finished condition prior to assembly or attachment to the cover or bottom of a hat box;

Figs. 4 and 5 are transverse cross sectional views of the holder blank as respectively viewed along the lines 4—4 and 5—5 in Fig. 3;

Fig. 6 is a perspective view of a fragmentary portion of the cover showing the holder with its ends partially raised out of the plane of the main surface of the cover, the latter being inverted with respect to its Fig. 1 position;

Fig. 7 illustrates a side elevational view of another conventional hat box having the holder secured to the base surface of the box bottom; and

Fig. 8 shows an arrangement wherein the holder is directly die cut out of an integral surface of the hat box which in this instance is cut from the large surface of the cover.

The hat box shown in Figs. 1 and 2 may be of any conventional shape or design but as one example comprises an octagonal box having a top 1 and a bottom 2, and a hat 3 is supported within the box by the holder 4, which is secured to the inside of the top 1.

For a better understanding of the holder 4, Figs. 3, 4 and 5 show the die cut holder blank B made from cardboard or from comparable material that will function equally as well to produce the action of this holder. The blank B in Fig. 3 is flat and symmetrical lengthwise and crosswise, and is divided into a gluing surface forming a base 5, with legs 6, 7 and 8 connected to one end of the base 5 and with legs 9, 10 and 11 connected to the other end of the base 5.

Leg 7 is staggered outwardly from the base 5 with respect to legs 6 and 8, while each of these three legs connect with the C-shaped hat gripping tongue 12. In the same manner leg 10 is also staggered outwardly from the base 5 with respect to legs 9 and 11, while these three legs connect with the C-shaped hat gripping tongue 13. Tongues 12 and 13 have centrally located recesses 14 and 15 at their ends to avoid crushing or deranging the hat bow while the tongues are in operative hat engaging position as a further aid in keeping the hat factory fresh and perfect in all respects.

The various described divisions of the blank B are due to the arrangement of slits and score

lines best shown in Fig. 3. Four longitudinal slits or die cuts are made longitudinally of the blank B comprising the aligned cuts 16 and 17, and the aligned cuts 18 and 19 with the latter parallel to the former as shown in this particular construction of hat holder 4. All the score lines are made transversely of the blank B and are indicated as 6a, 6b, 7a, 7b, 8a, 8b, 9a, 9b, 10a, 10b, 11a, and 11b, each pair comprising the terminal ends of the legs 6 to 11 respectively with the "a" figures designating the base ends of the legs and the "b" figures the tongue ends thereof.

Referring to Fig. 6 it will be noted that the described legs 6 to 11 are all arranged to move out of the plane of the blank B pivoting about their respect base score lines 6a to 11a, by which action the tongues 12 and 13 are raised and moved toward each other. To counteract this action and to introduce tension into this device to produce a holder having the properties hereinbefore set forth, a pair of rubber bands 20 and 21 are used to encircle the holder adjacent each of the leg groups at the opposite ends of the holder 4. The complete function of the bands 20 and 21, and the action of the holder 4 will later be explained.

The positioning of the rubber bands 20 and 21 is determined by a plurality of notches all arranged in predetermined locations chosen to create tension in certain directions and to keep the divisions of the blank B sturdy under the resilient pull of the bands. As seen in Fig. 3, aligned notches 22 and 23 are formed in the outer edges of the legs 6 and 8 at the swingable ends of these legs but offset to the leg side of the score lines 6b and 8b. Another pair of aligned notches 24 and 25 are formed on opposite edges of the intermediate leg 7 and adjacent the base 5 but to the leg side of the score line 7a.

These four notches 22 to 25 form the positioning means for the band 20 which is transversely looped about the holder 4 as best shown in Fig. 6. Similar notches 26, 27, 28 and 29 are arranged in like locations at the other end of the holder 4 and function to position the band 21 about the leg group at this end of the holder 4. Thus dual tensioning means are introduced at the ends of the hat holder in predetermined locations. Each tensioning means works independently of the other, and the band 20 restrains movement of the tongue 12 when the legs 6, 7 and 8 are moved about their respective score lines, while band 21 acts in the same capacity in regard to legs 9, 10 and 11.

The band notch locations have been carefully determined to avoid weakening of the blank divisions and to place the bands in positions for most effectively transmitting their resilient forces to the connected blank parts that cooperate to hold a hat. Notches 22—23 and 26—27 are all offset with respect to the adjacent leg score lines to prevent the bands from cutting through or into the blank along such score lines. But these notches are also cut in adjacent the outer swingable ends of these legs so as to move a greater distance out of the general plane of the blank.

The notches 24—25 and 28—29 are located near to the base score lines of the legs 7 and 10 respectively to hold the portions of the bands 20 and 21 looped about these legs in close proximity to the general place of the blank base 5. The blank B may be secured to the inside of the cover in any desirable manner but a suggested method is to cement or glue the cross-shaped base 5 to such box cover 1. Thus this central cross division of the blank B is held flat against the cover

with the attached legs being capable of moving upwardly out of this cover plane. Therefore, the notches 24-25 and 28-29 are each offset longitudinally outwardly with respect to the base 5 to establish clearance for the portions of the rubber band loops that pass under legs 7 and 10.

Since legs 6 to 11 are all of the same length and arranged as shown the movements of the tongues 12 and 13 are parallel with respect to the cover 1, and they move longitudinally inwardly toward each other so that the tongues will engage over the inner edge 30 of the hat band 31 of the hat 3 as best illustrated in Fig. 1. The rubber bands 20 and 21 will then approach their maximum tensioning positions holding the outer terminal ends of the tongues respectively outwardly to engage the inner opposite walls of the hat crown with the tongues over and above portions of the inner terminal or free upstanding edge of the hat band 31. By proportioning the leg lengths so as to cause the raised levels of the tongues to engage over and to abut the inner terminal edge 30 of the hat band 31 and considering the band 31 as the widest band used, the holder will also accommodate hats with bands varying under this width. The width of hat band is well standardized so variations are slight in this respect.

However, the variations in hat sizes will change the crown sizes, but attention is directed to the action of the holder when the legs are well raised as in Fig. 1. When the tongues are so located they may move outwardly or inwardly within a substantial range without affecting the elevation of the tongues under these relative positions so that the holder will automatically adjust itself to the different hat sizes and act to effectively retain the same with the tongues moving out or in as governed by the crown sizes and at the same time such tongues will move to the crown walls to abut over the inner edge of the hat band as described and as best seen in Fig. 1. Additional compensatory action is further possible when the inherent flexibility of the tongue ends is taken into consideration when such tongues are brought into hat holding position within the hat crown.

By using the fingers of one hand to engage opposite pairs of the leg sets the tongues are raised and drawn together to freely receive a hat crown thereover as placed in this position by the other hand. Moving the hat down toward the cover will cause the tongues to snap over the hat band 31 to urge the hat brim in the direction of the cover 1 thus holding the hat adjacent to the cover. Placing the cover upon the box bottom 2 centers the hat holder and obviously the hat as well. The general elliptical contour of the tongue ends blends into the hat crown shape as best seen in Fig. 2 allowing little, if any, chance of rotation of the hat about the vertical medial axis of the hat and hat box.

Some back and forth motion of the hat in the longitudinal direction of the blank B and box 2 is permissible by the rockable leg sets, but collapse of the legs is only limitedly allowable by the tongue or tongues against the edge 30 of the hat band 31 so as to prevent the hat brim or any part thereof from contacting the box periphery or wall.

To release the hat the fingers of one hand may be moved under one side of the hat brim to move any two of the legs of the opposite leg sets toward the middle of the blank B causing the tongues 12 and 13 to slide off the edge 30 of the band 31 thus freeing the hat for removal by the

other hand. The hand used to move the legs will also function to hold the cover and holder while the hat is being removed. The rubber bands 20 and 21 will then collapse the end movable assemblies in the direction of the original co-planar relations of the parts so that the latter may be left in this position or later raised to receive the same or some other hat.

In Fig. 7, all parts of the hat holder 4 are the same except that such holder is secured to the bottom 32 of a hat box 33 closed by a suitable cover 34.

In Fig. 8 the hat holder 4a is die cut out of the top wall 34 of the cover 35 of the hat box 36. This would leave openings such as 37 and 38 so it is desirable to add a closure or cover board 39 which can be cemented, glued or stapled to the top wall 34 to finish off the box and to cover the openings created by blanking the holder parts.

All other deviations and modifications relating to the hat holder construction of the present invention shall be governed by the breadth and scope of the language and limitations of the appended claims directed to this invention.

What I claim is:

1. A hat holder for retaining a hat with its open side disposed adjacent to a surface of a hat box, comprising a pair of tongues adapted for independent bodily movement in predetermined separate paths over said surface, and a plurality of leg members pivotally carried by said box and pivotally connected with each of said tongues respectively, said leg members for each tongue comprising a group arranged in staggered connected positions between the associated tongue and said box to suspend said tongue for bodily actuation into edge contact upon the upstanding free end of the sweat band of a hat.

2. A hat holder connected with one surface of a hat box to retain a hat with its open side facing said surface, comprising two movable assemblies adapted for independent movement relative to each other and with respect to the aforesaid surface, said assemblies each comprising swingable staggered legs movable out of the plane of said hat box surface and about parallel axes, said legs being of equal lengths, and a tongue connecting the free ends of said legs and having swinging movement relative to said legs about axes spaced and arranged as the aforesaid parallel axes and in parallelism therewith, said tongue comprising means for engaging over the upper edge of a sweat band of a hat while in contact with the hat crown adjacent the aforesaid edge to hold said hat by said band.

3. A hat holder connected with one surface of a hat box to retain a hat with its open side facing said surface, comprising two movable assemblies adapted for independent movement relative to each other and with respect to the aforesaid surface, said assemblies each comprising swingable staggered legs movable out of the plane of said hat box surface and about parallel axes, said legs being of equal lengths, and a tongue connecting the free ends of said legs and having swinging movement relative to said legs about axes spaced and arranged as the aforesaid parallel axes and in parallelism therewith, said tongue comprising means for engaging over the upper edge of a sweat band of a hat while in contact with the hat crown adjacent the aforesaid edge to hold said hat by said band for each assembly, and a resilient band connected with said staggered legs thereof to normally urge the latter into the plane of said box surface whereby the connected tongue

is biased toward the crown within said hat and against said edge of said sweat band of the hat.

4. A hat holder connected with one surface of a hat box to retain a hat with its open side facing said surface, comprising two movable assemblies adapted for independent movement relative to each other and with respect to the aforesaid surface, said assemblies each comprising swingable staggered legs movable out of the plane of said hat box surface and about parallel axes, said legs being of equal lengths, and a tongue connecting the free ends of said legs and having swinging movement relative to said legs about axes spaced and arranged as the aforesaid parallel axes and in parallelism therewith, said tongue comprising means for engaging over the upper edge of a sweat band of a hat while in contact with the hat crown adjacent the aforesaid edge to hold said hat by said band for each assembly, and a resilient band connected with said staggered legs thereof to normally urge the latter into the plane of said box surface whereby the connected tongue is biased toward the crown within said hat and against said edge of said sweat band of the hat, said legs having notched edges to receive portions of said resilient band therethrough to positively retain said band in operative relation during the relative movements of said legs.

5. A hat holder connected with one surface of a hat box to retain a hat with its open side facing said surface, comprising a pair of relatively movable members, cooperative means each comprising a plurality of legs pivotally connected with said one box surface for movement about a first set of spaced parallel axes, said legs having pivotal connections with one of said movable members on spaced axes parallel to each other and with respect to said first set of axes whereby said member is movable in successive parallel planes having predetermined spaced relations with respect to said box surface and with respect to each other, and independently operable means connected with each of said members to bias the same in a direction relatively outwardly within a hat crown and along said successive parallel planes into edge contact with spaced points along the free inner peripheral edge of the sweat band of said hat.

6. A blank for a hat holder comprising a length of flat board, a plurality of slits cut adjacent each end of said board and spaced from said ends thereof extending lengthwise of said board, parallel transverse scores formed in said board between said slits and from the slits to the board edges respectively with the latter scores disposed in staggered relation with respect to the aforesaid scores to provide swingable staggered leg sections movable out of the plane of said board, the intermediate portion of said board between the slits comprising a base for attaching said board to a hat box, and the end portions of said board beyond said slits providing spaced tongues each connected with the free ends of said swingable leg sections at each end of the board respectively and bodily movable toward and away from each other out of the plane of said board and base to function as retaining means to contact portions of a hat structure.

7. A blank for a hat holder comprising a length of flat board, a plurality of slits cut adjacent each end of said board and spaced from said ends thereof and extending lengthwise of said board, parallel transverse scores formed in said board between said slits and from the slits to the board edges respectively with the latter scores

disposed in staggered relation with respect to the aforesaid scores to provide swingable staggered leg sections movable out of the plane of said board, the intermediate portion of said board between the slits comprising a base for attaching said board to a hat box, and the end portions of said board beyond said slits providing spaced tongues each connected with the free ends of the swingable leg sections at each end of said board respectively and bodily movable toward and away from each other out of the plane of said board and base to function as retaining means to contact portions of a hat structure, certain of said legs having notches cut therein to receive a resilient band to normally hold the legs in the plane of said board and base.

8. In a hat confining and protecting means including a hat carrying surface and a hat, said hat being positioned with its crown located away from said carrying surface and with its head opening facing said surface to dispose the sweat band of the hat adjacent said surface, the improvement consisting of a hat holder in the form of a flat blank comprising a base connected with said hat carrying surface, a plurality of legs connected for swinging movement with respect to one portion of said base and disposed within said head opening of the hat, a plurality of legs connected for swinging movement with respect to another portion of said base and disposed within the head opening of said hat, and ledge members connected with the swingable ends of each plurality of legs respectively for disposition within the head opening of the hat and against spaced portions of the crown thereof, with portions of said ledge members engaging over the sweat band of the hat to hold the latter against said hat carrying surface of said confining and protecting means.

9. In a hat confining and protecting means including a hat carrying surface and a hat, said hat being positioned with its crown located away from said carrying surface and with its head opening facing said surface to dispose the sweat band of the hat adjacent said surface, the improvement consisting of a hat holder in the form of a flat blank comprising a base connected with said hat carrying surface, a plurality of legs connected for swinging movement with respect to one portion of said base and disposed within said head opening of the hat, a plurality of legs connected for swinging movement with respect to another portion of said base and disposed within the head opening of said hat, and ledge members connected with the swingable ends of each plurality of legs respectively for disposition within the head opening of the hat and against spaced portions of the crown thereof, with portions of said ledge members engaging over the sweat band of the hat to hold the latter against said hat carrying surface of said confining and protecting means, and tensioning means interposed between said ledge members and said base with said tensioning means constructed and arranged to normally urge said ledge members against said hat crown and in the direction of the base so as to maintain the ledge members in contact with the upper edge of the sweat band of the hat.

10. A hat holder connected with one surface of a hat box to retain a hat with its open side facing said surface, comprising two movable assemblies adapted for independent movement relative to each other and with respect to the aforesaid surface, said assemblies each comprising

ing swingable staggered legs attached to said box surface, a ledge connecting said legs and bodily movable upon the swingable ends of said legs, and resilient means connected with the swingable ends of certain of the legs and extending diagonally to the attached box surface end of a staggered leg for connection with said leg and to urge all of said legs in a direction to actuate said ledge into contact with the upper peripheral edge of a sweat band within a hat.

11. A hat holder for a hat box comprising a box wall portion, two movable assemblies adapted for independent movement relative to each other and with respect to the said wall portion, each assembly comprising a plurality of legs each pivotally connected with said wall portion at points staggered laterally with respect to each other and in the direction of movement of the assembly, and a ledge pivotally supported upon the outer swingable ends of said legs of each assembly and arranged to contact the inside of the hat crown

adjacent the inner free edge of the sweat band of a hat and to engage the inner edge of said band.

PAUL E. NELSON.
